WINDOW SHADE ROLLER

Horace S. Peed, Denver, Colo.

Application December 13, 1945, Serial No. 634,655

5 Claims. (Cl. 160—298)

1

This invention relates to window shades and analogous devices, and more particularly to roller-supported, flexible-sheet type window shades, curtains, and the like, and has as an object to provide improved roller mounting, actuating, and positioning means for such devices.

A further object of the invention is to provide improved window shade roller mounting, actuating, and positioning means adapted for operative association with conventional shade roller mounting brackets.

A further object of the invention is to provide improved window shade roller mounting, actuating, and positioning means effective in use to obviate many of the disadvantages of conventional spring-type shade rollers.

A further object of the invention is to provide improved window shade roller mounting, actuating, and positioning means susceptible of ready operative adaptation, with identical advantage, to and for the selective manipulation of particularly prepared new rollers or conventional spring-type rollers such as are now in general use.

A further object of the invention is to provide an improved construction and operative combination of elements constituting spring-free window shade roller mounting, actuating, and positioning means.

A further object of the invention is to provide an improved construction and operative combination of elements constituting window shade roller mounting, actuating, and positioning means susceptible of selective operative association with particularly prepared or conventionally standard roller constructions.

A further object of the invention is to provide an improved construction and operative combination of elements constituting window shade roller mounting, actuating, and positioning means adapted to modify but one end of the roller without in any way altering the operative relationship of such roller with conventional roller-mounting brackets.

A further object of the invention is to provide an improved window shade roller mounting, actuating, and positioning unit that is simple and inexpensive of manufacture and operative installation, susceptible of practical development in various ornamental aspects from various readily-available specific materials, convenient of manipulation to the accomplishment of the ends for which designed, and operatively efficient throughout a long life of practical use.

With the foregoing and other objects in view, my invention consists in the construction, ar-

2

rangement, and combination of elements herein-after set forth, pointed out in my claims, and illustrated by the accompanying drawing, in which—

5 Figure 1 is an end elevation of the improved unit as assembled and arranged for practical use in association with a shade roller. Figure 2 is a side elevation of the unit shown in Figure 1 with separable elements of the unit assembly spaced apart for greater clarity of illustration. Figure 3 is a cross section taken substantially on the indicated line 3—3 of Figure 1 and showing the unit of said latter figure in operative association with a conventional shade and roller assembly. Figure 4 is a cross section taken on the indicated line 4—4 of Figure 3, shade and roller elements of said latter figure being omitted. Figure 5 is a fragmentary, detail section, similar to Figure 3, of the construction employed in adapting the unit to use with particularly prepared shade rollers.

Conventional spring-type roller shade assemblies long extensively used in association with windows and for analogous purposes are quite generally similar in operative principle and construction and characterized by operative disadvantages and annoyances too well known to require comment. The conventional roller shade assembly includes a straight, cylindrical roller of suitable size and material, commonly wood, a suitably-sized sheet of flexible material, such as fabric, paper, or the like, secured at one end to and rolled closely about the roller, a mounting pin fixedly projecting axially from one end of the roller for journaled reception in the bearing aperture of a mounting bracket, an elongate bore axially and opening through the other end of the roller, a cap fixedly closing the otherwise open bore end in fixed connection with the adjacent end of an elongate coil spring housed 10 within the roller bore, a stem axially and rotatably intersecting said cap and extending interiorly of said spring to fixed connection of its inner end to the spring inner end, whereby rotation of said stem relative to the cap and roller acts to apply torsional stress to said spring, a ratchet connection between said stem and cap, and an angular mounting lug engageable in a slotted mounting bracket formed on the exterior end of said stem outwardly beyond said ratchet connection. All 15 of the foregoing is usual roller shade construction typical, with slight mechanical variations, of the devices presently in use, and is cited only to identify the elements and relationships wherewith the improved unit may be operatively associated to 20 preserve the major investment of existing instal-

lations represented by the conventional roller and its shade sheet.

The improved unit is designed to eliminate the spring and ratchet elements of conventional constructions and to retain, with enhanced convenience, facility, and advantage of operative manipulation, the conventional roller and shade assembly, to which end the unit is designed to be mounted on and to cooperate with the bored end of a conventional roller in the manner shown in Figure 3, and in such mounting and cooperation to engage with the usual roller brackets wherein such roller shade assemblies are normally carried. In adapting the improved unit to and for operative association with conventional shade rollers, the latter are modified by cutting away from the roller the cap closing the roller bored end and removing from the said roller the spring and stem assembly associated with said cap, thus opening the bore at the roller end to free and unobstructed access; the fixed pin at the other roller end and the flexible sheet and roller association being undisturbed and retained to accomplish their original functions in the manner for which they were initially assembled.

The improved unit to be associated with the roller shade assembly as above modified includes a peripherally-grooved wheel 10, preferably moulded, pressed, or otherwise suitably formed as an integral element from any material having the requisite properties of hardness and durability, such as metal, various plastics, hard rubber, and the like, through one side face whereof opens an axially-disposed, conveniently-cylindrical recess of relative considerable size and of an axial length less than that of said wheel. As clearly appears in the views of the drawing, the wheel 10 preferably has a maximum diameter slightly greater than that of the roller wherewith it is to cooperate, a recess diameter equal to or slightly less than that of the roller bore, a recess axial depth such as to leave a web of substantial thickness completing the uninterrupted wheel side face; a peripheral groove width axially of the wheel slightly less than twice the diameter of a cord 11 to be received therein, and a peripheral groove depth radially of the wheel slightly less than the said cord diameter. The peripheral groove profile may conform with any specific outline suited to the functional association of wheel 10 and cord 11, and preferably includes rounded corners adapted for large-area contact with cord surfaces engaged thereagainst. The wheel 10 axial recess is adapted to telescopically receive and engage with a suitably-sized mounting boss 12 formed for such purpose as or on the end of a cylindrical plug 13 of relatively soft wood or similar material, the length of which plug 13 exterior to the wheel 10 is sized to telescopically engage and fit closely within the bore 14 of a conventional spring-type roller 15 modified by removal of its end closure cap and associated spring as above set forth. The engaged wheel 10 axial recess and boss 12 surfaces may be conjoined by means of glue, cement, and the like, to inhibit relative motion therebetween, and a gudgeon pin 16, having a shouldered, cylindrical head 17, engages through a hole formed for such purpose axially through the wheel 10 unrecessed face web and is driven or pressed into axial penetration of the boss 12 and bearing relation of its head shoulder against the wheel 10 outer face such as will secure said wheel in firmly-seated relation on said boss with the gudgeon pin head 17 projecting axially and exteriorly beyond the so-mounted wheel.

The plug 13 is joined to and fixed within the bore of the roller 15 with the adjacent face of the wheel 10 abutted against the roller end, any suitable and convenient means for fixedly interconnecting said plug and roller being employed, so that manipulations had with rotative effect on said wheel are transmitted through the boss 12 and plug 13 to rotate the roller 15 and correspondingly wind and unwind relative thereto a flexible shade sheet 18 secured at one end to said roller in the usual manner.

The wheel-equipped end of the roller 15 is rotatively engaged and operatively associated with a mounting cup or bridle 19 adapted for removable and replaceable, non-rotatable connection with a conventional slotted roller shade bracket. The cup 19 is preferably cast, moulded, or pressed from suitable rigid material, conveniently the same as that forming the wheel 10, and comprises an axially-short, cylindrical base portion having a diameter greater than the maximum wheel diameter, a semi-circular, marginal flange 20 forming a skirt integrally outstanding axially from one face of said base portion, a conformably-arcuate, marginal finger 21 integrally outstanding axially from the base portion in bisecting relation with the marginal arc not occupied by the skirt 20 and partially completing the orbital projection of the latter, a hole axially intersecting the face of the base portion overhung by the skirt 20 and finger 21, hence concentric with said skirt and finger elements, and sized to receive and rotatably mount the gudgeon pin head 17, and an angular lug 22 outstanding centrally and axially from the base portion face remote from the skirt and finger. When the cup 19 is formed from material other than metal, it may be expedient in the interest of strength and durability to form the base portion thereof as a circular web surrounding and fixedly engaging with a metallic central core 23 wherein and whereon are formed the gudgeon pin head mounting hole and lug 22, in substantially the manner illustrated by Figure 3. The depth and internal diameter of the cup formed by the skirt 20, finger 21, and base portion are such as to freely receive and house the wheel 10 when the gudgeon pin head 17 is journaled in the hole provided in the base portion for such purpose, and the lug 22 is sized and shaped to engage within the conventional mounting slot of an ordinary roller shade mounting bracket, the disposition of said lug on its cup being so correlated with the positions of the skirt and finger as to dispose said finger at the bottom and said skirt at the top of the assembly when bracket-mounted for operation. The cup internal diameter is so proportioned to the wheel peripheral groove minimum diameter as to leave a space between the groove bottom of the mounted wheel and the skirt and finger inner surfaces slightly less than the diameter of the cord 11, so that when said cord is engaged therebetween it is compressed slightly by and held in frictional relation with said bottom and surfaces, thereby minimizing any tendency of the wheel and associated roller to rotate relative to the mounting cup 19.

The cord 11 used to complete and to manipulate the improved device may be of any specific character and manufacture suited to its purpose, and may be employed in the form of a suitable length having separate ends or in the form of an endless loop of convenient length, as shown in Figure 1, the latter being preferred. In either event, an intermediate portion of the cord 11 is

wrapped one and one-half times about and in the peripheral groove of the wheel 10 so that the cord loops lie side by side in the upper arc of the groove and the cord lengths depend from opposite sides of the wheel, and the so-corded wheel is then entered into the mounting cup 19 with the finger 21 engaging between and separating the depending cord lengths and the skirt 20 frictionally embracing the double loop wheel periphery. As so arranged and assembled, the improved unit is ready for mounting and use, it being necessary only to insert the pin end of the roller in the conventional bracket, engage the lug 22 at the other roller end in the usual slotted bracket, and the assembly is mounted with the cord 11 lengths depending from one end of the assembly. When and as so mounted, a pull on one of the cord lengths operates to rotate the wheel, roller and shade assembly in one direction for extension or retraction of the shade sheet relative to the roller, while a pull on the other cord length operates to rotate the assembly in the opposite direction for reversal of shade travel, the cup 19 being held by the lug 22 against rotation while the roller assembly rotates on and about its fixed pin at one end and the journal mounting of the gudgeon pin head 17 in the cup base at its other end. Due to the extent of its length engaged therewith, the frictional grip of the cord 11 about the wheel 10 is greater than the friction between said cord and the cup 19 skirt and finger elements, so that while the cord friction relative to the mounting cup is sufficient to at all times hold the shade and roller in any adjusted position, a pull on either of the depending cord lengths functions to rotate the wheel and roller relative to the cup rather than to slip the cord about the wheel.

When it is desired to associate the improved unit in and with new roller shade constructions, as distinguished from use of the unit to convert existing roller shade assemblies, the bored roller 15 and plug 13 may be replaced by a single, solid roller construction 15' having an integral axial boss 12' formed on one of its ends to engage with and mount the wheel 10, as shown in Figure 5, the other end of said roller 15' being furnished with an axially-disposed fixed mounting pin in the usual and conventional manner. Use of the solid roller 15' contributes to convenience and economy of new roller shade assembly in that it obviates the expense and trouble of the roller-boring operation and avoids the waste incident to removal and discard of the conventional cap, spring, and stem elements of spring-type rollers.

Since many changes, variations, and modifications in the specific form, construction, and arrangement of the elements shown and described may be had without departing from the spirit of my invention, I wish to be understood as being limited solely by the scope of the appended claims, rather than by any details of the illustrative showing and foregoing description.

I claim as my invention:

1. The combination with a cylindrical roller having a mounting pin fixedly projecting axially from one of its ends and a flexible sheet operatively associated with and for extension and retraction relative to said roller, of a peripherally-grooved wheel fixed to and in axial coincidence with the other roller end, an actuating cord frictionally engaging about said wheel in said groove, a mounting pin fixedly projecting axially and exteriorly from said wheel, a mounting cup housing said wheel in frictional engagement with the groove-positioned cord, an axial journal bearing

in said cup rotatably accommodating said wheel pin, spaced slots longitudinally of the cup cylindrical wall for the accommodation of depending cord portions, and a bracket-engageable angular mounting lug fixedly projecting axially and exteriorly from said cup.

2. In a roller shade assembly having a cylindrical roller equipped with a fixed, axially-projecting mounting pin at one end and a flexible sheet associated with and for extension and retraction relative to said roller, roller mounting, actuating, and positioning means comprising a peripherally-grooved wheel fixed to and in axial coincidence with the other roller end, an actuating cord engaging circumferentially and frictionally about said wheel in said groove and depending from opposite sides thereof, a mounting pin fixedly projecting axially and exteriorly from said wheel, a mounting cup rotatably housing said wheel in journaled relation with said wheel pin and frictional engagement with the wheel-mounted cord, and an angular lug axially and exteriorly of said cup bracket-engageable to mount and non-rotatably hold the latter.

3. In a roller shade assembly having a cylindrical roller equipped with a fixed, axially-projecting mounting pin at one end and a flexible sheet associated with and for extension and retraction relative to said roller, roller mounting, actuating, and positioning means comprising a peripherally-grooved wheel fixed to and in axial coincidence with the other roller end, an actuating cord engaging circumferentially and frictionally about said wheel in said groove and depending from opposite sides thereof, a mounting pin fixedly projecting axially and exteriorly from said wheel, a mounting cup rotatably housing said wheel in journaled relation with said wheel pin and frictional engagement with the wheel-mounted cord, spaced slots longitudinally of the cylindrical cup wall for accommodation of the depending cord portions, and an angular lug fixed axially and exteriorly of said cup bracket-engageable to mount and non-rotatably hold the latter.

4. Roller mounting, positioning, and actuating means for operative association with roller shade assemblies, comprising a wheel mountable on and in fixed, axially-coincident relation with one end 50 of the assembly roller, a mounting pin fixedly projecting axially from said wheel, a groove peripherally of said wheel, an actuating cord having a diameter greater than said groove depth engaging circumferentially and frictionally about said wheel in said groove and depending from opposite sides thereof, a mounting cup rotatably housing said wheel in journaled relation with said wheel pin and frictional engagement with the wheel-mounted cord, spaced slots longitudinally of the cylindrical cup wall for accommodation of the depending cord portions, and a bracket-engageable angular lug fixedly projecting axially and exteriorly from said cup.

5. Roller mounting, positioning, and actuating means for operative association with roller shade assemblies having roller elements formed with an axial, cylindrical boss on one each of their ends, comprising an axially-recessed wheel telescoped over and fixed to said roller end boss, a shouldered gudgeon pin axially intersecting said wheel and engaging said boss to dispose its outer end as a mounting pin axially exterior to said wheel, an actuating cord engaging circumferentially and frictionally about said wheel and depending from opposite sides thereof, a mounting cup housing

said wheel in journaled relation with said gudgeon pin exterior end and frictional engagement with the wheel-mounted cord, spaced slots longitudinally of the cylindrical cup wall for accommodation of the depending cord portions, and a bracket-engageable angular lug fixedly projecting axially and exteriorly from said cup.
